UNITED STATES PATENT OFFICE.

WILLIAM W. TALBOT, OF NEW YORK, N. Y.

CLINICAL THERMOMETER.

1,119,202.

Specification of Letters Patent.

Patented Dec. 1, 1914.

Application filed June 30, 1914. Serial No. 848,148.

To all whom it may concern:

Be it known that I, WILLIAM W. TALBOT, a citizen of the United States, residing at New York, in the city, county and State 5 of New York, have made a certain new and useful Invention in Clinical Thermometers, of which the following is a specification.

This invention relates to clinical thermometers.

10 The object of the invention is to provide means which are simple and efficient for causing the mercury or other temperature responsive element of thermometers to be forced down toward or into the bulb of the 15 thermometer without danger of breaking or injuring the thermometer.

A further object is to provide a thermometer structure of the nature referred to 20 wherein, in case of accidental breakage of the thermometer the broken part may be easily, readily and economically replaced.

Other objects of the invention will appear more fully hereinafter.

The invention consists substantially in the 25 construction, combination, location and relative arrangement of parts, all as will be more fully hereinafter set forth, as shown in the accompanying drawing, and finally pointed out in the appended claims.

30 Referring to the accompanying drawing,—Figure 1 is a view in elevation showing a clinical thermometer applied to a case or holder in accordance with my invention preparatory to manipulation for forcing the 35 mercury or other temperature element down in the bulb of the instrument. Fig. 2 is a view in longitudinal central section of the case or holder showing the thermometer housed therein. Fig. 3 is a broken view in 40 enlarged central longitudinal section of one end of the thermometer and its housing case. Fig. 4 is a transverse section on the line 4, 4, Fig. 3.

The same part is designated by the same 45 reference numeral wherein it occurs throughout the several views.

In the construction of clinical thermometers it is customary to make the tube with the bulb in the ordinary way and to seal 50 a metal cap over the open end of the tube by means of cement, this cap being exteriorly threaded to afford means for securing the thermometer into a case. This is an objectionable practice for the reason that 55 the cement seal frequently is impaired by the sterilizing operations to which the ther-

momter must be repeatedly subjected, thereby loosening the cap on the end thereof. Moreover, in case of breakage of a thermometer, and experience has demonstrated 60 that these devices are exceedingly delicate and fragile, where the screw cap sleeve is cemented over the end of the tube, not only must the tube be thrown away but also the screw cap sleeve must be thrown away. 65 This cap sleeve, and the cost of attaching the same adds materially to the cost of the complete article. Moreover, in ordinary use it is necessary to frequently force the mercury or other temperature element of 70 the thermometer toward or down into the bulb. Where this is done by quickly shaking or jarring the tube the danger is incurred of breaking the fragile tube and so destroying the instrument. Various devices have 75 been prepared for utilizing flexible spring holders or torsional spring connections to act upon the thermometer in order to force the mercury down into the tube. Such devices as have heretofore been employed for 80 this purpose, however, have not proven to be entirely satisfactory, and besides have been costly to manufacture.

It is among the special purposes of my present invention to avoid the objections 85 noted and to provide a thermometer in which the open end of the tube is closed by fusing the glass or other material of which the tube is made and shaping the same into a shouldered head. Over the tube I loosely slip a 90 metal sleeve which is exteriorly threaded and adapted to be drawn endwise against the headed end of the tube. A metal cap is then telescoped over the headed end of the tube and is threaded onto the exteriorly threaded 95 sleeve. With this construction in case of breakage of the tube the sleeve and cap are easily removed and applied to another tube and it is only necessary, therefore, to renew or replace the tube itself which costs 100 much less than a tube with its end cap sealed to it. This arrangement also permits repeated sterilizations of the thermometer without danger of impairing a cement or other adhesive connection of the cap to the 105 tube.

In order to provide efficient and safe means for forcing the mercury or other temperature responsive element of the thermometer down into or toward the bulb of 110 the tube, I provide a case in which the tube is ordinarily carried and in one end of this

2
tube I permanently secure a swivel for axially rotative movement, and I provide the swivel with spring clamp jaws and a knob to be grasped by the operator. The tube 5 with its cap sleeve is inserted or threaded through the clamp jaws so that the shank of the cap sleeve is received and clamped between the clamp jaws. Now, by holding the case vertically, with the tube clamped and held as described, and giving a quick rotation to the clamp swivel the tube is revolved thereby permitting centrifugal action to cause the mercury or other temperature responsive element to be forced into or 15 toward the bulb of the tube.

Referring to the drawing, reference numeral 5, designates the thermometer tube, one end which is provided with a bulb 9, and the other end is closed by a fused and flanged head 7. The tube 5 may be of the usual 20 or any desired shape in cross section, and may be graduated in the ordinary way of clinical or other thermometers. Slipped loosely over the tube 5 is an exteriorly 25 threaded sleeve 10, and a cap 11, telescoped over the closed head 7 of the tube and screwed onto the sleeve 10, serves to draw the latter endwise up against the flange on the head 7, as clearly shown. The sleeve 10 is provided with an extended cylindrical 30 shank portion 12, for a purpose presently to be described. The tube is to be carried in a case 13, which may be of the usual size to carry in the pocket, the tube with its cap 35 and sleeve being inserted endwise in the case and held firmly therein by exterior threads on the cap 11, engaging interior threads formed in the mouth of the case. A sleeve 14 is inserted in the other end of 40 the case and rigidly secured therein. The stem 15 of a swivel is journaled for axial rotation in the sleeve 14. This swivel has its ends split to form spring jaws 16, 17, which are coöperatively shaped to form a cylindrical 45 spring clamp 18, the ends of said jaws being extended and coöperating to form a knob or handle 19 adapted to be grasped between the fingers of the operator for the purpose of axially rotating said 50 swivel. By unscrewing the cap 11, from the threaded mouth of case 13 the thermometer tube is withdrawn from the case for use. After it has been used and it is desired to restore the mercury or other 55 temperature responsive material to or toward the bulb 9, the tube is inserted endwise through the spring clamp 18 until the cylindrical portion or extension 12 of the sleeve 10 is embraced by said clamp and 60 securely held by friction therein the spring action of the jaws 16, 17, securing this result. Now by grasping the knob 19 of the swivel between the fingers and giving the

swivel a sharp whirl while holding the case 13, in proper position the tube 5 is revolved 65 with the swivel in a horizontal plane and through centrifugal action the mercury or other temperature responsive element is forced to or toward the bulb.

In case of the tube becoming broken from 70 any cause the cap 11 and sleeve 10 are removed therefrom and placed on a new tube. By the construction described I am enabled to avoid breakage of the thermometer but in case a tube should be accidentally broken 75 it is readily replaced at small cost. It can also be sterilized repeatedly without danger of destroying the cement or other adhesive connection of the screw cap to the tube.

The complete device with the case is rendered 80 readily salable as an article by reason of repeat orders for the tubes themselves, and, if desired, the name and address of the retail dealer may be applied to the case for advertising purposes.

Having now set forth the objects and nature 85 of my invention and a construction embodying the principles thereof, what I claim as new and useful and of my own invention and desire to secure by Letters Pat- 90 ent is,

1. A clinical thermometer including a tube having a bulb at one end and an integrally closed head at the other end, a sleeve loosely slipped over the tube and provided with a cylindrical extension, a cap telescoped freely over the closed head of the tube and engaging the sleeve in combination with a case having a swivel, said swivel having spring clamp jaws to receive and clamp the 100 cylindrical extension of said sleeve when the latter is inserted endwise there through.

2. A clinical thermometer having a bulb at one end and an integrally closed head at the other end, a sleeve loosely slipped over 105 the thermometer and provided with a cylindrical extension, a removable screw cap telescoped over said closed head and engaging said sleeve, a case for the thermometer having a swivel rotatively mounted in one end 110 thereof, said swivel having jaws coöperating to form a spring clamp to receive and hold the cylindrical extension of the sleeve when the thermometer is inserted endwise through said clamp, said jaws having extensions to form a knob or handle for rotating said swivel.

In testimony whereof I have hereunto set my hand in the presence of the subscribing witnesses, on this 2nd day of June A. D., 12 1914.

WILLIAM W. TALBOT.
